UNITED STATES PATENT OFFICE.

WILLIAM E. DELEHANTY, OF ALBANY, AND EDWARD J. MURPHY, OF GREENBUSH, NEW YORK.

AUTOMATIC TRAP FOR WASH-BASINS.

SPECIFICATION forming part of Letters Patent No. 326,277, dated September 15, 1885.

Application filed August 15, 1884. (No model.)

To all whom it may concern:

Be it known that we, WILLIAM E. DELEHANTY, of the city and county of Albany, in the State of New York, and EDWARD J. MURPHY, of Greenbush, in the county of Rensselaer and State of New York, have invented certain new and useful Improvements in Automatic Traps for Wash-Basins, &c., of which the following is a specification.

- 10 Our invention relates to improvements in automatic traps for the waste-water pipes of wash-basins and other similar apparatus; and the objects of our invention are to provide suitable self-operating devices for preventing 15 the inflow of noxious gases through the waste-water pipe, and to utilize the weight of the waste water, in combination with its floating properties, for automatically operating the valve of the trap. These objects we attain 20 by means of the mechanism illustrated in the accompanying drawings, which, being herein referred to, form part of this specification, and in which—

Figure 1 is a vertical section of our invention as applied to a wash-basin; Fig. 2, a detached vertical section of part of the trap-chamber, showing the trap-valve open; Fig. 3, an enlarged plan view of rosette for the valve-rod; and Fig. 4, an enlarged vertical 30 section of same, showing the manner of locking the valve-rod in its raised position.

As represented in the drawings, A is a wash-basin of the usual and well-known form, and B the slab which forms the top of the 35 casing; C, the trap-chamber; D, trap-valve; E, waste-water pipe from basin to trap-chamber; F, branch pipe from cap of trap-chamber to float-chamber; G, float-chamber; H, float; I, valve-rod, and J handle of valve-rod.

40 The trap-chamber C is a separate vessel, preferably made of glass, and provided with a detachable metallic cover, C', which has a transverse passage, e, across its upper face, and a pendent pipe, e', attached to or formed 45 upon its lower face, so as to form a continuous communication with the transverse passage e.

An outlet-pipe, e'', is connected to one side of the chamber C, near its upper end, and is 50 connected by means of a suitable waste-water pipe to the drainage system of the building

wherein this device is used. The outlet-pipe e'' is provided on its inner end with a hood, c'', which projects downward inside of the chamber C to a point below the water-line of 55 said chamber.

The waste-pipe E is connected to the transverse passage e, so as to deliver the water from the basin A directly into said passage. The branch pipe F is connected to extend vertically from one end of the transverse passage e to the under side of the float-chamber G, which latter is secured to the under side of the slab B at a point that is conveniently adjacent to the basin A. 60

The branch pipe F is provided with a slip-joint which works in a stuffing-box, f, for the purpose of adjusting the apparatus to different heights of wash-stands.

The float H is fitted to reciprocate freely 70 in a vertical direction in the float-chamber G, and is provided with a pendent sleeve, h, through which the valve-operating rod I passes freely; but said rod has no fixed connection to the float H. 75

The valve-operating rod I is preferably made of a tube which is arranged inside of the branch pipe F, and is connected by means of an adjustable joint to the extension-piece i, which passes freely through a conical seat, 80 e', secured to or formed on the cover C' of the trap-chamber. Said extension-piece is provided with a valve, i', which fits upon the seat e', so as to form a water and gas tight joint at that point when the valve-operating 85 rod is pushed down to its lowest point of movement to close the trap-valve D; and, as will be seen in Fig. 1, when said trap-valve is closed against the end of the pipe e', the valve i' will also be closed down upon its seat e', so 90 as to effectually close the latter point against any leakage of the water from the pipe F, and prevent the escape of any sewer-gas through the opening through the seat e'. Within the trap-chamber C the extension-piece i is pivoted to the outer end of the lever d, which is 95 hereinafter fully described. The upper end of the rod I is provided with a socket, i'', having at its lower end projecting arms, or a flange, i''', against which the float H as it rises 100 will engage to move said rod in an upward direction. The downward movement of said

rod is facilitated by means of a weight, i^4 , which is attached to said rod.

The handle J is attached to the socket i^2 by means of a stem, j , provided with a flange, j' , which engages with the upper end of said socket in such manner that the rod I can be lifted by the float H without raising the handle J ; or, when required, said rod may be lifted by means of said handle. The handle J is provided with wings j^2 , which are adapted to slide in the notches k of a rosette, K , that is secured to the upper side of the slab B . The wings j^2 are so arranged that, when the handle J is raised and turned a partial revolution, said wings will rest on the top of the rosette K and retain the rod I in its raised position.

The valve D is composed of a hollow india-rubber ball, that is fitted to move upwardly and seat against the lower end of the pendent pipe c' , and to form a tight joint therewith. Said valve is disconnected from any operating mechanism, so as to be free, when relieved from a superimposed pressure, to be floated upward in the water, which will always lie in the trap-chamber C , and thereby effect the closing of the opening through the pendent pipe c' , whether the valve-operating rod I is in position to effect the closing of the valve or not. Guides d' are formed on the lower end of the pendent pipe c' , for the purpose of guiding the valve D and preventing its displacement. The lever d is fulcrumed to one of the guides d' . The outer end of said lever is pivoted to the extension piece i , and its inner end is pivoted to a cup, d^2 , which bears against the inner side of the ball-valve D .

The automatic operation of our apparatus is as follows: The basin A being filled or partially filled with water, on the removal of the stopper from the outlet of said basin the water will pass down through the waste-pipe E and up through the branch pipe F into the float-chamber G . When sufficient water is collected in said chamber, the float H will rise, and thereby the rod I will be lifted to relieve the valve D from the pressure of said rod and the weight i^4 , which pressure (through the intervention of the lever d) tends to force said valve upward in close contact with the seat. As soon as the valve D is so relieved the weight of the superincumbent water acting on the valve forces it from its seat and permits the water to pass out through the trap-chamber C and outlet-pipe c^2 until an equilibrium is established to permit the rod I to fall and effect the return of the valve D to its seat. When required, the handle J can be held in the raised position, as hereinbefore described, and shown in Fig. 4, thereby relieving the valve from the upward pressure due to the rod I and weight i^4 when in the last-named condition. Whenever the weight

of water bearing upon the upper side of the valve is sufficient to overcome the floating power of the water below the valve, the latter will be forced from its seat to permit the water to escape, as above described, until the floating power of the water in the chamber C exceeds the pressure acting upon the upper side of the valve D , whereupon the latter will be automatically restored to its seat.

It will be seen that all outlets for the escape of gases from the sewers are effectively sealed by the upward seating of the valve D and the downward seating of the valve i^4 . By the upward sealing of the valve D we remedy a well-known defect in traps in which the sealing is effected by a downward movement of the valve, which defect consists in the liability of the valve to be raised by a sudden influx of gas or a back-pressure in a system of connected waste-pipes, wherein the waste water from an upper story is apt to back up and raise an upward-opening valve from its seat.

We claim as our invention—

1. The combination, with a waste-water pipe, E , for a wash-basin or other similar article, and a branch pipe, F , connecting said waste-water pipe with the float-chamber G , of the trap-chamber C , provided with an outlet-pipe, c^2 , the trap-valve D , arranged inside of the trap-chamber C , and adapted to close with an upward movement against the lower end of the pendent pipe c' , the valve-operating rod I , and float H , as and for the purpose herein specified.

2. The combination, with a trap-chamber, C , having a detachable cover, C' , containing an upwardly-closing valve, D , and provided with an outlet-pipe, c^2 , and conical seat c^4 , of the valve-operating rod I , provided with the valve i^4 , arms i^3 , and weight i^4 , lever d , and the float H , all being constructed and arranged to operate substantially as and for the purpose herein specified.

3. The combination, with a trap-chamber, C , having a detachable cover, C' , with a pendent pipe, c' , the said trap-chamber being provided with an outlet-pipe, c^2 , which is above the plane of the lower end of the pendent pipe c' , of the upwardly-closing valve D , contained inside of the trap-chamber C , and resting loosely on a cup, d^2 , attached to the free end of the lever d , the said lever being connected to a weighted operating-rod, I , provided with a float, H , all being constructed and arranged to operate substantially as and for the purpose herein specified.
